UNITED STATES PATENT OFFICE.

JOHN L. CHAPPELL, OF LOS ANGELES, CALIFORNIA, ASSIGNOR TO UNION ART GLASS & FIXTURE CO., OF LOS ANGELES, CALIFORNIA, A PARTNERSHIP COMPOSED OF J. L. CHAPPELL, B. E. RIEG, AND E. B. WILLIAMS.

DESIGN FOR A COMBINED LANTERN AND BRACKET.

Application filed February 11, 1926. Serial No. 16,485. Term of patent 3½ years.

To all whom it may concern:

Be it known that I, JOHN L. CHAPPELL, a citizen of the United States, residing at Los Angeles, in the county of Los Angeles and State of California, have invented a new, original, and ornamental Design for a Combined Lantern and Bracket, of which the following is a specification, reference be-

ing had to the accompanying drawing, forming part thereof.

The figure is a perspective view of the combined lantern and bracket therefor.

I claim:

The ornamental design for a combined lantern and bracket, as shown.

JNO. L. CHAPPELL.
